(57) CLAIM

The ornamental design for a bottle, as shown and described.

DESCRIPTION

FIG. 1 is a perspective view of a bottle showing our new design;

FIG. 2 is a front elevational view thereof; and,

FIG. 3 is a top plan view thereof.

The dash-dot-dash-dot broken lines shown in the drawings are for environmental purposes only and form no part of the claimed design. The dash-dot-dot-dot-dot broken lines shown in the drawings define the boundary of the claim.
